Patented July 6, 1976

240,387

COMBINED SALT AND PEPPER DISPENSER

John W. Downey, Warren, Pa., assignor to Whirley Industries, Inc., Warren, Pa.

Filed Aug. 16, 1974, Ser. No. 497,845

Term of patent 14 years

Int. Cl. D7—06

U.S. Cl. D7—56

Fig. 1

Fig. 2

FIG. 1 is a perspective front view of a combined salt and pepper dispenser embodying my new design; and

FIG. 2 is a perspective back view of a combined salt and pepper dispenser embodying my new design.

The portions of the combined salt and pepper shaker dispenser not shown in the drawings are plain and unornamented.

I claim:

The ornamental design for a combined salt and pepper dispenser, as shown and described.
